UNITED STATES PATENT OFFICE.

J. FREDERICK APPELL, OF CHICAGO, ILLINOIS.

SHIRT.

SPECIFICATION forming part of Letters Patent No. 228,721, dated June 15, 1880.

Application filed March 9, 1880. (No model.)

To all whom it may concern:

Be it known that I, J. FREDERICK APPELL, of Chicago, State of Illinois, have invented certain new and useful Improvements in 5 Shirts; and I do hereby declare that the following is a full, clear, and exact description thereof, reference being had to the accompanying drawings, and to the letters of reference marked thereon, which form a part of this 10 specification.

My invention relates to a novel construction in three-ply-bosomed shirts, the objects of which are to obtain the utmost uniformity in the thickness of the bosom throughout its entire extent and to fortify the body at the 15 bosom-edge against breaking. The latter purpose is effected much as shown in Letters Patent No. 224,265, granted to me February 10, 1880—namely, by the extension of the innermost ply of the bosom beyond the outermost; but in the construction herein shown I obtain a greater uniformity in thickness between the bosom-edge and its body by making 20 the middle ply narrower than the outer one, the middle ply narrower than the outer one, 25 as will be fully explained.

In the drawings, Figure 1 shows a shirt-front containing my improvement in elevation, and Figs. 2, 3, and 4 are fragmentary sections through the marginal seams.

30 A is the bosom, composed of the three plies *a*, *b*, and *c*, and B is the body of the shirt. The innermost ply, *c*, is made wider than the outermost, *a*, when folded under at its edge, and the middle ply, *b*, is made narrower than 35 the outermost, as clearly seen in the several sectional figures.

Three marginal rows of stitching are necessary to secure the several edges in this construction, as follows: First, the outer row, *d*, 40 secures the under bosom-ply, *c*, to the shirt-body B; the middle row, *e*, secures the outer

ply, *a*, the shirt-body B, and, preferably, the under ply, *c*; and the inner row, *f*, secures the middle ply, *b*, preferably, to both the outer ply, *a*, and the innermost ply, *c*. The middle ply, *b*, should fall within the inturned edge of the outer ply, *a*, as shown in all the sectional figures. If the several parts joined were of equal thickness, they might be indifferently arranged, as shown in these figures; but as the outer or 50 face ply, *a*, is usually very thin, and as the middle ply, *b*, and the body-stuff B ordinarily correspond nearly in thickness, I prefer the arrangement shown in Fig. 2, wherein these parts abut or lie in the same plane without 55 overfolding.

As will be seen by reference to Fig. 2, the bosom is no thicker at its extreme edge than inside the seam *f*, except by one thickness of the thin outer ply, *a*, where folded under, 60 which is imperceptible in the finished article. In respect of uniformity of thickness throughout the entire extent of the face ply or bosom proper, the device here shown is an improvement on that shown in the aforesaid Letters 65 Patent granted to me.

Having thus described my invention, I claim—

In a three-ply-bosomed shirt, the under ply, *c*, extended beyond the outer ply, *a*, and beneath the shirt-body B, and the middle ply, *b*, made narrower than the outer ply, and secured by the inner row of stitching, *f*, substantially as described.

In testimony that I claim the foregoing as 75 my invention I affix my signature in presence of two witnesses.

J. FREDK. APPELL.
